X-RAY TUBE

Filed June 6, 1931

Inventor:
Walter Hofmann,
by Charles E. Tullar.
His Attorney.

UNITED STATES PATENT OFFICE

WALTER HOFMANN, OF ERLANGEN, GERMANY, ASSIGNOR TO GENERAL ELECTRIC COMPANY, A CORPORATION OF NEW YORK

X-RAY TUBE

Application filed June 6, 1931, Serial No. 542,671, and in Germany February 4, 1930.

In the case of X-ray tubes provided with an anode adapted to rotate relatively to the cathode stream, the well known advantages of a line-focus, annular area of electron impact cannot be fully obtained, owing to those portions of the annular area of impact which are nearer to the axis of rotation moving at a slower linear speed than the portions further removed from the axis of rotation.

10 In accordance with the present invention, this disadvantage is eliminated by increasing the intensity of the electron bombardment of the anode in proportion to the distance of the point of impact from the axis of rotation.

15 One method, for example, of bringing about this result is to diminish the distance between the turns of the heated filament in inverse proportion to their distance from the axis of rotation.

20 In the form of construction shown by way of example in the accompanying drawing, the rotating anode 1 is arranged to turn on its longitudinal axis by means of well known devices. The cathode comprises the focusing device 2 and the spirally shaped, heated filament 3. The distance between the respective turns of the filament decreases from the right to the left as shown, thus causing an increase in electron emission as the outer end 25 of the filament is approached. Consequently, the intensity of the bombardment of the anode becomes greater from the inner edge to the outer edge of the area of impact 4. In view, however, of the greater peripheral speed of the outer edge, the difference in the 30 terminal load is substantially compensated.

What I claim as new and desire to secure by Letters Patent of the United States is:

1. An X-ray tube including an envelope 40 and provided with an anode adapted to rotate, and a line focus cathode, said cathode comprising a helical filament whose turns are spaced closer together as the end of the filament remote from the anode axis of rotation 45 is approached.

2. An X-ray tube including an envelope and provided with an anode adapted to rotate and an electron emitting cathode, said cathode being adapted to emit electrons in increasing numbers as the portion of the 50 cathode remote from the anode axis of rotation is approached.

3. An X-ray tube including an envelope and provided with an anode adapted to rotate, and a line focus cathode, said cathode 55 comprising a helical filament whose turns are spaced continuously closer together in proportion to the relative distances of the respective turns from the anode axis of rotation.

4. An X-ray tube including an envelope and provided with an anode adapted to rotate, and a line focus cathode, said cathode comprising a helical filament, the spacing between the turns being inversely proportional 65 to the linear speed corresponding to the distance of the turn from the anode axis of rotation.

In witness whereof, I have hereunto set my hand.

WALTER HOFMANN.
